UNITED STATES PATENT OFFICE

140,682

DESIGN FOR A TOY

Maxine Stuart, New York, N. Y.

Application December 7, 1944, Serial No. 116,770

Term of patent 7 years

(Cl. D34—15)

To all whom it may concern:

Be it known that I, Maxine Stuart, a citizen of the United States of America, residing in New York city, county of New York, and State of New York, have invented a new, original, and ornamental Design for a Toy, of which the following is a specification, reference being had to the accompanying drawing, forming part thereof, wherein,

The rear of the toy is substantially the same in appearance as the front.

I claim:

The ornamental design for a toy, substantially as shown and described.

MAXINE STUART.
